UNITED STATES PATENT OFFICE

2,468,087

THERMIONIC VALVE CIRCUITS

Maurice Moise Levy, London, England, assignor, by mesne assignments, to International Standard Electric Corporation, New York, N. Y., a corporation of Delaware

Application January 18, 1944, Serial No. 518,704
In Great Britain January 29, 1943

7 Claims. (Cl. 250—27)

1

The present invention relates to thermionic valve circuits, and in particular to means for stabilising the operation of such circuits against variations in the voltage of the supply source for the valves.

In the specification of British Patent No. 563,222 arrangements are described for stabilising the performance of a thermionic valve circuit when the voltage of the high tension supply source varies. The operating voltages and currents of such valve circuits are however frequently obtained from a commercial alternating current supply the voltage of which is rarely constant and in such a case the stabilisation of the circuit can be effected rather more simply by an arrangement controlled by the voltage variations of the main alternating supply itself. In this way, also, the combined effects of all the variable supplies derived from the main source may be simultaneously dealt with.

According to the invention, therefore, there is provided an arrangement for stabilising the operation of an electric wave translating or generating device which includes one or more thermionic valves supplied with operating potentials and currents from an alternating current source of variable voltage, comprising means for deriving from the source a unidirectional control voltage varying in accordance with the voltage variations of the source and means for applying the control voltage to the device in such a manner as to render its performance substantially independent of the said voltage variations.

According to another aspect, the invention comprises an electrical circuit arrangement comprising an alternating current source of variable voltage, means for deriving therefrom appropriate operating voltages and currents for a wave translating or generating circuit containing thermionic valves, and means for applying to one or more of the valves a unidirectional control voltage adapted to vary in accordance with the voltage variations of the source in such manner that the characteristics of the valve circuit are rendered substantially independent of the said voltage variations.

The invention will be described with reference to the accompanying drawing, in which:

Fig. 1 shows a block schematic diagram to explain the principle of the invention;

Fig. 2 shows a schematic circuit diagram of an embodiment; and

Fig. 3 shows diagrams to explain the operation of Fig. 2.

Fig. 1 shows in block schematic form the prin-

2

ciple of the invention. A load circuit L, which may be an amplifier, oscillator, modulator, or any other type of circuit employing thermionic valves, is supplied with operating potentials from an alternating current main supply transformer PT through a power unit PU containing appropriate rectifying and smoothing arrangements. This unit may be of any suitable known type, and may provide any number of different voltages and currents which may be necessary. The voltage of the main supply will usually be subject to variations from time to time, which may quite commonly reach $\pm 10\%$, and generally such variations cause corresponding variations in the characteristics or performance of the load circuit L. For example, if this circuit is an amplifier, the gain will usually increase or decrease when the supply voltage increases or decreases, the relation being approximately linear for moderate variations of the supply voltage. Similarly if the load circuit is an oscillator, the frequency and/or the output current or voltage may vary in a similar sort of way.

To compensate for the effect of these variations, a unidirectional control voltage varying in accordance with the main supply voltage variations is derived from the transformer PT and is applied to the load circuit in such a manner as to counteract the changes produced by the main supply variations. One preferred method is to apply the control voltage to a grid of one or more of the valves in the load circuit L in a manner similar to that described in the patent referred to above. In this case it is necessary to arrange so that the control voltage varies in opposite sense to the main supply voltage.

In Fig. 1 the control voltage v is obtained by means of the control unit CU which is supplied with an alternating voltage V_1 from the transformer PT. In one form of the control unit to be described below, a continuous voltage is required for its operation. This may be obtained from a battery, or it may be produced in the control unit if desired by suitable rectifying means; but since a high tension voltage will be usually needed for the valves in the load circuit L, this voltage will be available at the output of the power unit PU, and is preferably used for the control unit as indicated in Fig. 1, where it is designated V_2 .

The schematic circuit diagram of Fig. 2 shows a preferred form of the control unit CU of Fig. 1. A diode D has the cathode connected to earth through a neon tube N (or other suitable gas discharge tube) and is connected through a resistance R_3 to the positive terminal of a source

of continuous voltage, which is preferably the high tension supply derived from the power unit PU (Fig. 1), the negative terminal of which supply is commonly (or can be) connected to ground. The cathode accordingly assumes a fixed positive potential V_3 determined by the neon tube N, which potential is independent of the variations of V_2 . The anode of the diode is connected through a condenser C_1 to a tapping point on a resistance potentiometer formed by the resistances R_4 and R_5 connected in series across the transformer PT (Fig. 1), so that an alternating voltage V_4 , which is a known fraction of V_1 , is applied through the condenser C_1 , to the anode of the diode.

The load on the diode D comprises the series connected resistances R_4 , R_5 and R_6 , the condensers C_2 and C_3 being provided for smoothing purposes according to well known principles. The resistance R_6 is provided with an adjustable tap from which an appropriate control voltage v may be obtained for application to the load circuit L (Fig. 1).

The action of the circuit of Fig. 2 will be understood from the diagram shown in Fig. 3. The curve A indicates the alternating voltage applied to the diode; the line V_4 represents the maximum positive amplitudes of A, and is supposed to vary between the limits V_4 max. and V_4 min. represented by the corresponding dotted lines. The cathode voltage V_3 is represented by the chain dotted line, and should be chosen to be a little less than V_4 min.

When the instantaneous positive voltage of the curve A exceeds the value V_3 , the condenser C_1 charges through the diode in such a manner as to reduce the anode potential so that it becomes negative to the cathode. If the capacity of the condenser C_1 and the total resistance $R_4+R_5+R_6$ be chosen so that the time constant of the circuit is large compared with the period of the alternating current supply, the condenser will not be able to discharge appreciably between the successive positive loops of the curve A.

The condenser C_1 will accordingly acquire a difference of potential substantially equal to V_4-V_3 , and the terminal connected to the anode will be negative; and it is from this difference of potential that the control voltage v is derived. The function of the diode is primarily to charge the condenser, and it can be disregarded from the point of view of the control voltage since it passes no current except just at the tips of positive loops of the A curve. There is thus applied to the resistances R_4 , R_5 , R_6 a continuous voltage V_4-V_3 , derived from the condenser in series with an alternating voltage V_4 derived from the resistance R_2 , and the current due to this alternating voltage is substantially shunted away by the condensers C_2 and C_3 . If R_2 be chosen small compared with $R_4+R_5+R_6$, then the maximum available value of v (which is the voltage drop across R_6) is very nearly equal to

$$\frac{R_6(V_4-V_3)}{R_4+R_5+R_6}$$

and moreover is of opposite sign to V_4-V_3 as indicated by the plus and minus signs in Fig. 2.

In order to assist in the choice of appropriate elements for the circuit of Fig. 2, the following particulars of a practical circuit are given for illustration. It will of course be understood that other values of the elements may be used in other circumstances.

In this particular case the alternating voltage

V_1 was 280 volts R. M. S., the peak amplitude being therefore about 400 volts. The variation of the supply was $\pm 10\%$. The high tension voltage V_2 derived from V_1 in the power unit was 250 volts $\pm 10\%$.

The resistances and condensers in the circuit of Fig. 2 had the following values:

R ₁ , R ₃ and R ₆ -----	megohm--	1
R ₂ -----	do	0.2
R ₄ and R ₅ -----	do	0.5
C ₁ -----	microfarad--	0.01
C ₂ and C ₃ -----	do	0.2

The neon tube produced a constant voltage difference of 70 volts and the current flowing through it was about 180 microamperes.

The diode D can be very small, adapted for a current of the order of 1 milliampere, for example such as may be used in television apparatus. Actually in the circuit of Fig. 2, the current which flows through the diode will be much less than 1 milliampere.

It will be seen that with the above values, the maximum amplitude V_4 is 80 ± 8 volts, so that the potential acquired by the condenser C_1 varies from -18 to -2 volts. Neglecting R_2 in comparison with $R_4+R_5+R_6$, it will be seen that the maximum available value for the control voltage v varies from -9 to -1 volts.

It will be seen that the load on the power supply is negligible. The current taken from the transformer PT is less than 300 microamperes (R. M. S.) and that taken from the high tension supply at voltage V_2 is less than 300 microamperes.

It will be noted that in this circuit, the supply voltage is stepped down by means of the potentiometer to a value such that V_4 min. is only slightly greater than the voltage V_3 determined by the neon tube. The variations are stepped down in the same ratio. If therefore, two or three, similar neon tubes be used in series, a smaller step down ratio of 5:2, or 5:3, may be used, so that the variations are doubled, or trebled. The corresponding range of the maximum values of v will be -18 to -2 volts and -27 to -3 volts.

With $V_2=250$ volts, more than three neon tubes of course cannot be used, but it will be evident that if a higher value V_2 is employed, four or more such tubes become possible. The maximum number of neon tubes is determined by the requirement that there must be at least 70 volts available for each. For other types of gas filled tubes, the fixed voltage may of course be different from 70 volts.

The arrangement of the smoothing circuit (which in Fig. 2 comprises the resistances R_4 , R_5 and condensers C_2 and C_3) can be varied according to known principles in any desired way, or a non-dissipative wave filter could be used if preferred, though this would be much more bulky and expensive than the simple arrangement shown. However, for any smoothing or filtering arrangement used, the same control voltage will be obtained if the total load resistance is made equal to $R_4+R_5+R_6$.

It is to be noted, also, that any other convenient means may be used for stepping down the alternating voltage V_1 to V_4 . For example, the resistances R_1 and R_2 could be replaced by a suitable step-down transformer; or in Fig. 1, the control unit could be connected to an appropriate tap on the secondary winding of the transformer PT.

Furthermore, in Fig. 2 the diode D could be replaced, if desired, by some other kind of recti-

fier such as a copper oxide or selenium rectifier connected so that the forward direction is from the condenser C_1 to the neon tube N , or by a triode or other valve biassed to the cut off so that it operates as a rectifier in substantially the same way as the diode D .

It is to be pointed out that the control voltage v can be reversed in sign if desired by inverting the diode D (or other equivalent rectifier) and reversing the voltage V_2 ; the circuit operates as described above except that the condenser C_1 will now be charged with the opposite polarity, and the charging is performed by the negative loops of the wave A (Fig. 3) instead of by the positive loops. This requires that the source of the voltage V_2 should have the positive terminal connected to ground; and if this is not permissible for the power unit PU , the voltage V_2 may be obtained from a separate source.

It will be observed that the control unit shown in Fig. 2 does not require any modification to be made to the power unit PU nor in general to the load circuit L , which will usually already have terminals conveniently adapted for applying a bias to the control grids or other grids of the various valves.

What is claimed is:

1. An electrical circuit comprising a source of alternating voltage of variable amplitude, a first rectifier means connected across said source for obtaining a first unidirectional voltage, a load supplied by said rectifier means including at least one thermionic valve having an anode and cathode connected across said first rectifier means, means for comparing said first unidirectional voltage from said first rectifier means with at least a portion of said alternating voltage to produce a voltage difference corresponding to the variable peaks of said alternating voltage, a second rectifier means for rectifying said voltage difference to obtain a second unidirectional voltage in accordance with the peaks of one polarity, and means for applying said second unidirectional voltage to a control electrode of a thermionic valve of said load in the proper phase and amplitude to nullify the effect of variations of the voltage from said source by means of the fluctuations of said second unidirectional voltage and to render the output of said load substantially independent of variations from said source.

2. A circuit according to claim 1, in which said comparing means include a condenser controlled by a voltage proportional to said alternating voltage and by said first unidirectional voltage to produce a voltage difference therebetween.

3. A circuit according to claim 1, wherein said comparing means include a condenser controlled at one terminal by a potential derived from said alternating voltage and at the other by a potential derived from said first unidirectional voltage, at least one gas discharge tube, said tube being supplied with current derived from said first unidirectional voltage both said condenser and said gas tube being serially connected with said second rectifier means.

4. A circuit according to claim 1, wherein said comparing means include a condenser controlled

by a voltage proportional to said alternating voltage and by said first unidirectional voltage to form a voltage difference therebetween, said second rectifier having an input circuit including said condenser and a gas discharge tube, said tube being supplied with current derived from said first unidirectional voltage, and having an output circuit including a resistance load, and means for applying at least a part of said resistance load to bias the thermionic valve of said load.

5. A circuit according to claim 1, wherein said comparing means include a condenser controlled by said alternating voltage and said unidirectional voltage to produce a voltage difference therebetween, said second rectifier means having an input circuit including said condenser and in series therewith at least one gas discharge tube, said tube being supplied with current derived from said unidirectional voltage, and an output circuit including a resistance load, means for smoothing said resistance load, and means for applying at least a portion of the smoothed resistance load to bias a thermionic valve of said load.

6. A circuit according to claim 1, wherein said comparing means including a condenser controlled by a voltage proportional to said alternating voltage and by said first unidirectional voltage to produce a voltage difference therebetween, said second rectifier means having an input circuit including said condenser and an output circuit controlling the input circuit of a thermionic valve of said load, said condenser being arranged to be charged by the positive peaks of one polarity and said second rectifier means being arranged to produce a second unidirectional voltage of negative polarity.

7. A circuit according to claim 1 in which said comparing means includes a condenser controlled by said alternating voltage and said first unidirectional voltage to form a voltage difference therebetween, and said second rectifier means includes a diode having an anode circuit and a cathode circuit, a gas discharge tube connected in said cathode circuit and connected to be supplied with current from said first unidirectional voltage, said anode circuit being connected through said condenser to said source of alternating voltage, and a resistance connected between said anode and cathode for developing thereacross said second unidirectional voltage.
